UNITED STATES PATENT OFFICE.

JOHN FRANCIS KEYES, OF SPRINGFIELD, MASSACHUSETTS.

MILLING VISE.

Application filed August 26, 1920. Serial No. 406,210.

To all whom it may concern:

Be it known that I, JOHN F. KEYES, a citizen of the United States of America, residing at Springfield, in the county of Hampden and State of Massachusetts, have invented certain new and useful Improvements in Milling Vises, of which the following is a specification.

This invention relates to improvements in vises and the leading object of the invention is to provide a vise with a quick returnable movable jaw, the invention being particularly designed for use in a milling vise in which quantity production is involved and the output is increased by eliminating motions, though the invention can be applied to any form of a vise.

One of the objects of the invention is to provide a vise with a movable jaw which may be advanced to clamping position by means of a screw, a separable nut for disengaging the movable jaw from the screw and a spring or like device for imparting rapid motion to the movable jaw to return the same when the nut is disengaged from the screw.

Another object of the invention is to provide means for adjusting the spring to vary the tension thereof.

With the above and other objects in view this invention relates to certain new and useful constructions, combinations and arrangements of parts, clearly described in the following specification and fully illustrated in the accompanying drawings, in which:

Fig. 1 is a top plan view partly in longitudinal section.

Fig. 2 is a transverse sectional view.

Fig. 3 is a longitudinal sectional view.

Referring to the accompanying drawings 5 designates a table or base having a movable jaw 6 slidable thereon against the rigid jaw 7 provided on said table or base 5. The movable jaw is provided with a base 8 having key lugs 8^a thereon to engage the key ways 5^a formed in the table or base 5, whereby the movable jaw will be slidably interlocked with the base or table 5. The movable jaw is shown to be provided with an integral side wall 9 and a detachable side wall 10

having an integral top 11, the side wall 10 being secured to the base of the movable jaw by means of screws 12 or the like and the top wall 11 being secured to the side wall 9 by screws 13 or the like.

Within the chamber provided by the hollow movable jaw, a pair of separable nut sections 14 and 15 are mounted to slide upon the key ways 16 formed in the base of the movable jaw, and the sections or members 14 and 15 are provided with right and left threads 17, engaged by the right and left threads 18 of the screw shaft 19, one end of which has a bearing 19^a on the side wall 10 and the other end of which 19^b extends through the side wall 9 and is engaged by the crank 20 whereby the same may be rotated. When the crank 20 is rotated in one direction the section or members 14 and 15 will be moved toward each other and when it is rotated in the opposite direction the sections or members will be moved away from each other. The male and female threads are preferably triple so that a rapid motion will be imparted to the sections 14 and 15 when the crank 20 has been moved a short distance, such as a third of a revolution, and the nut sections 14 and 15 will be separated from each other a sufficient distance to safely clear the thread of the propelling screw 21, which is mounted to rotate in the bearing 22 provided on the base 5 and which extends between the sections 14 and 15 to have threaded engagement therewith 85 and which carries an operating crank 23 on its outer end.

The movable jaw is forcibly shifted by means of the expansion spring 24, the forward end of which engages the upstanding arm 25, and the rear end of which engages the screw 29 of the movable jaw. The arm 26 works in a groove 25^a formed in the base 8 of the movable jaw, and said arm is provided with a lateral stem 28, which is secured to the lower end of the arm 25. The stem 28 extends through the slot 28^a formed in the base 5 and is held in adjustable position by means of the nut 27, which is threaded on the stem 28 against the side of the base 5, as shown in Fig. 1. By adjusting the stem on the base the relation of the arm 25

to the expansion spring 24 will be varied, and the tension of the spring may be adjusted. The screw 29 is adjusted by means of the head 30, to vary the tension of the spring.

When the nut sections 14 and 15 are moved away from each other the expansion spring will expand against the adjustable stop 25 and return the movable jaw to its initial position. When the screw 21 is operated to move the movable jaw toward the rigid jaw to clamp the work the spring will be placed under compression so that the spring will always function to return the movable jaw and release the work clamped between the two jaws.

The invention is particularly designed for use in connection with milling vises and simplifies the motions required to remove the work after being milled, but the invention is capable of application to any type of vise, bench or otherwise.

Having described my invention I claim:—

1. A vise comprising a rigid jaw, a jaw movable relatively thereto, a screw for propelling the movable jaw, separable nut sections for connecting the movable jaw to the screw, means for moving the nut sections toward and away from each other, and means for moving the movable jaw away from the rigid jaw releasable when the nut sections are disengaged from the propelling screw.

2. A vise comprising a fixed jaw, a jaw movable relatively to the fixed jaw, a screw for moving the movable jaw relatively to the fixed jaw, means for connecting the movable jaw with the screw, and means for shifting said connecting means to disengage said screw from said movable jaw including a right and left threaded screw.

3. A vise comprising a fixed jaw, a jaw movable relative thereto, a spring for moving said movable jaw away from said fixed jaw, a screw, and means carried by the movable jaw for engaging said screw to permit the screw to propel said movable jaw, said means being disengageable from said screw to permit the spring to return the movable jaw to its initial position.

4. A vise comprising a fixed jaw, a jaw movable relative thereto, means for imparting a quick motion to the movable jaw, a screw shaft for propelling the movable jaw in one direction, a nut carried by the movable jaw and adapted to have operative engagement with the screw shaft, and a worm shaft for moving the nut into and out of engagement with the screw shaft.

5. A vise comprising a fixed jaw, a jaw movable toward and away from the fixed jaw, a worm shaft for propelling the movable jaw, a second worm shaft disposed transversely of the first worm shaft, and a

nut having operative engagement with the second worm shaft and adapted to be propelled thereby into and out of engagement with the first worm shaft, whereby the movable jaw may be propelled by the action of said first worm shaft or otherwise.

6. A vise comprising a bed having a fixed jaw thereon, a movable jaw slideable on the bed, a split nut slideable on the movable jaw, a worm shaft for moving the sections of the split nut in opposite directions simultaneously, and a worm shaft having a bearing on the bed and threaded engagement with the split nut, whereby the movable jaw may be propelled on the bed.

7. A vise comprising a bed having a fixed jaw, a movable jaw thereon, a main propelling worm shaft having a bearing on the bed, divided means providing a driving engagement between the movable jaw and the shaft movable transversely of the shaft in opposite directions, means for simultaneously moving the divided means toward or away from each other and adapted to resist the displacement of said first named means under the load transmitted by said main shaft, whereby said first named means may be disengaged from the main shaft, and means for propelling the movable jaw in a reverse direction when the first named means is disengaged from the main shaft.

8. A vise comprising a bed having a fixed jaw thereon, a jaw movable on the bed toward and away from the fixed jaw, a spring for rapidly moving the movable jaw away from the fixed jaw, a screw for propelling the movable jaw toward the fixed jaw and for placing the spring under tension, a nut carried by the movable jaw for engaging the screw, and means carried by the nut for moving the same out of engagement with the screw to permit the spring to react and propel the movable jaw away from the fixed jaw.

9. A vise comprising a bed and a fixed jaw thereon, a jaw movable toward and away from the fixed jaw, a spring having a bearing at one end with the movable jaw to propel it away from the fixed jaw, an adjustable stop for the other end of the spring providing means for varying its tension, a screw for propelling the movable jaw, and means for establishing and disestablishing driving engagement between the screw and the movable jaw.

10. A vise comprising a bed having a fixed jaw thereon, a movable jaw on the bed, a screw for propelling the movable jaw on the bed, a right and left threaded screw carried by the movable jaw, and means controlled by said right and left threaded screw for establishing and disestablishing a driving engagement between said right and left threaded screw and the movable jaw.

11. A vise comprising a bed having a fixed jaw thereon, a movable jaw on the bed, a spring having a bearing at one end on the bed and at the other against the movable jaw, a screw for propelling the movable jaw, guides on the movable jaw, nut sections slideable horizontally on said guides, and a right

and left threaded screw journaled on said movable jaw and working through the nut sections to move said nut sections toward 10 and away from each other.

Signed by me at Springfield, Massachusetts.

JOHN FRANCIS KEYES.
